WINDSHIELD CLEARING SYSTEM

Erwin C. Horton, Hamburg, N. Y., assignor to
Trico Products Corporation, Buffalo, N. Y.

Application July 30, 1938; Serial No. 222,183

4 Claims. (Cl. 20—40.5)

This invention relates to means for maintaining clear vision through windows, more particularly the windshields of motor vehicles, and it has for its primary object to provide improved means for delivering a vision clarifying fluid to the transparency in an efficient manner, and further it has for its purpose to provide practical means for applying a heated fluid to the glass to facilitate its solvent action on vision obscuring matter and thereby expedite the removal of the latter.

The invention also contemplates the raising of the temperature of the clearing fluid by practical means and with a view toward conservation of its supply.

In the drawing

Fig. 1 is a view illustrating the present invention incorporated in a motor vehicle;

Fig. 2 is a sectional view of the pump;

Fig. 3 is a similar view of the fluid heater;

Fig. 4 is a detailed view depicting a branched delivery pipe for plural deliveries; and

Fig. 5 is a sectional showing of the shut-off valve.

Referring more particularly to the drawing, the numeral 1 designates a wiper reciprocated on the windshield glass 2 by a motor 3. A jet or nozzle 4 is disposed on the cowl to throw fluid or liquid upwardly onto the glass in the path of the wiper as it is delivered thereto by a pump 5 which receives a charge of liquid from the reservoir 6. The pump may be suction operated and is herein depicted as being connected to the intake manifold 7 of the vehicle engine 8 by a line of communication 9 which has an interposed and readily accessible shut-off or control valve 10. When the valve is depressed against its spring 11 to block the atmospheric vent 12 the kerf or slot 13 and its connected bore 14 will establish communication between the pump and source of low pressure to draw up the diaphragm or piston 15 against the urge of its spring 16 and thereby intake a charge of fluid from the reservoir 6. Upon releasing the shut-off valve the vent 12 will equalize the pressure in the motor chamber 17 of the pump and permit the spring 16 to function by forcing the piston downwardly for expelling the liquid through the delivery pipe 18 to the nozzle. By reason of the vent 12 the pressure differential is dissipated so as to permit such spring action without requiring the attention of the motorist during the delivery of the solution. Inlet and outlet check valves 19 and 20, respectively, are properly located for the greatest efficiency and cooperate to provide unidirectional flow of the clearing fluid through the pump. The valve 20

may be rendered accessible through a removable cap 20'. The delivery pipe may be divided, Fig. 4, where plural nozzles are provided.

The present arrangement contemplates raising 5 of the temperature of the clearing fluid to increase its effectiveness in removing the objectionable vision obscuring matter from the field of vision. Warm or hot liquid, when ejected onto the glass, will more readily soften and dissolve 10 the matter for easy removal. Advantage is gained by merely heating one charge of the liquid at a time to facilitate matters, although a larger volume may be treated, if desired. In the preferred embodiment the next charge of liquid to 15 be emitted will be heated after passage through the pump and thereby prolong the useful life thereof. To conserve this heated liquid charge against waste, through vaporization or boiling out through the nozzle, the temperature to which the 20 liquid is brought prior to charge is kept substantially below its boiling point. This may be practically accomplished by utilizing the heat from the vehicle engine in an indirect or controlled manner.

25 Accordingly, the illustrated embodiment has a heating unit in the form of a liquid coil 21 in heat exchange contact with the water in the engine jacket. It may be disposed within the inlet pipe 22 leading to the hot water heater 23 for 30 the passenger compartment of the vehicle and which has its return pipe indicated at 24. For ease of insertion a separate length of pipe 25 may be interposed in the usual flexible inlet pipe. The length of the coil and its adjacency to the discharge nozzle 4 will determine the proportion of 35 the entire charge directly heated by the engine cooling system. If the preliminary portion of the charge is relatively cool it will nevertheless serve to wet the glass for expediting the subsequent 40 action of the warmer liquid.

Preferably, the volume of liquid retained in the delivery pipe or passage 18, which connects the pump to the nozzle, is substantially equal to the 45 volumetric discharge from the pump during a full liquid ejecting stroke thereof.

From the foregoing it will be observed that the charge of liquid to be discharged onto the windshield will be preheated to a practical degree in a simple manner. The hot liquid is kept from 50 passing through the pump and is delivered direct to the nozzle. Should the operation of the pump be repeated immediately after one charge the length of coil and the temperature of the engine cooling medium will determine the extent of heating the clearing liquid will derive while resting

therein during the intaking stroke in addition to the interval of flow therethrough.

While the foregoing description has been given for clearness of understanding, it is not the intention thereby to restrict the invention which may assume other physical embodiments without departing from the spirit thereof or the scope claimed.

I claim:

1. A window clearing system for a motor vehicle having an engine having a hot fluid flow, comprising means arranged on the vehicle to deliver a vision clearing liquid onto the vehicle windshield, a source of liquid supply connected by a line of communication to said delivery means, a pump for supplying comparatively small charges of liquid from said source to said delivery means at intervals, and a heater unit interposed in the line between the pump and the delivery means and in heat exchange contact with the hot fluid for deriving heat therefrom to warm the charge of liquid during the rest period between such intervals whereby the pump is maintained free of the heated liquid.

2. A window clearing system for a motor vehicle having a hot water passage in circuit with the engine cooling system, comprising a nozzle for delivering a volume of window clearing fluid onto a vehicle window for maintaining clear vision therethrough, a source of supply for the fluid, means for delivering small charges of the fluid from the source to the nozzle with intervening periods of rest between charges, and a heat transfer unit common to both fluid systems and removably inserted in the hot water passage as a part thereof, said unit having a fluid passage connecting at one end to the source and at the opposite end to the nozzle for heating the next charge of fluid during the preceding period of rest.

3. A window clearing system for a motor vehicle having an engine with a circulating cooling medium, comprising a nozzle arranged on the vehicle to deliver a vision clearing liquid onto the vehicle windshield, a source of liquid supply connected by a line of communication to said nozzle, a heating unit interposed in the line in heat exchange contact with the circulating cooling medium for being heated thereby, and a pump interposed in the line between the source of liquid supply and the heating unit for delivering the liquid under pressure through the unit to said nozzle and having a liquid intaking stroke and an expelling stroke, the volumetric capacity of the line of communication between the pump and nozzle inclusive of the heating unit being substantially equal to that of the pump on its discharge stroke whereby each discharge of liquid from the nozzle will be acted upon by the heating unit during the interval between expelling strokes of the pump.

4. A window clearing system for a motor vehicle comprising a nozzle arranged on the vehicle to deliver a vision clearing liquid onto the vehicle windshield, a source of clearing liquid supply connected by a line of communication to said delivery means, a pump connected for feeding the clearing liquid under pressure to said delivery means, said pump having a spring pressed piston connected by a conduit to a source of fluid pressure for being operated on one stroke by a fluid pressure differential counteracting the spring urge, and manual means for closing the conduit to the pressure source and simultaneously opening it to the atmosphere to permit spring actuation of the piston, the spring actuated stroke of the piston acting to force the liquid through the nozzle.
